UNITED STATES PATENT OFFICE.

BENJAMIN GREENBERG AND MORRIS TARNOFF, OF NEW YORK, N. Y.

MANUFACTURE OF SKINS FOR FUR COATS.

Application filed May 12, 1927. Serial No. 190,779.

This invention relates generally to the manufacture of fur coats, and has more particular reference to a novel method of cutting and arranging the skins therefor.

5 The invention has for an object the provision of a method of cutting and arranging the skins of a rabbit for the purpose of producing furs for the manufacture of fur coats of a relative light colour when compared with 10 the entire rabbit's skin.

The invention has for a further object the provision of a method of cutting and arranging the skins of a fur coat for the purpose of making an imitation squirrel coat, which 15 can be manufactured and sold at a very reasonable cost.

For further comprehension of the invention and of the objects and advantages thereof, reference will be had to the following description and accompanying drawing, and to 20 the appended claims in which the various novel features of the invention are more particularly set forth.

Referring to the accompanying drawing 25 forming a material part of this disclosure:

Fig. 1 is a plan view of a rabbit skin, with dot-dash lines thereon indicating the cutting thereof according to the invention method.

Fig. 2 is a plan view of the two portions 30 cut from the skin seen in Fig. 1 sewed together.

Fig. 3 is a sectional view taken on the line 3—3 of Fig. 2.

Fig. 4 shows the utilization of the skins 35 of Fig. 2 in the formation of material for the coat.

The reference numeral 10 indicates a rabbit's skin having a neck portion 11, tail portion 12, paw portions 13, back 14 and belly 40 portions 15.

Practically without exception, the belly portions of rabbits are of a light color, and very similar to squirrel skins. The instant invention takes advantage of this fact by 45 cutting the skin along dot-dash lines 16, that is, including the belly portions and a portion of the back 14, and of such shape so as to substantiate half a squirrel's skin.

As shown in Fig. 2, these portions are next 50 sewn together along the cut lines 16^a, by

means of stitches 17. The skin thus produced resembles a squirrel skin inasmuch as it is of a relatively light color, has a back portion 14', lighter colored belly portions 15', paws 13', and a head portion 11'. A rubberized 55 strip of material may be secured to the back of the skin.

The complete skins of Fig. 2 may be indicated by numeral 18 for a simple understanding of Fig. 4. In this figure a plurality 60 of these skins 18 are shown joined together along their edges to form the material of the coat, and then the hairs of the fur are cut to the same lengths.

While we have illustrated and described 65 our invention with some degree of particularity, we realize that in practice various alterations therein may be made. We therefore reserve the right and privilege of changing the form of the details of construction 70 or otherwise altering the relation of the correlated parts without departing from the spirit or the scope of the appended claims.

Having thus described our invention what we claim as new and desire to secure by 75 United States Letters Patent is:

1. A method of making fur skins for use in the manufacture of fur coats comprising the longitudinal cutting of strips of skins from a rabbit skin, said strips comprising a longitudinal back section and an adjacent longitudinal belly section, and sewing of said strips together with the longitudinal back sections thereof adjacent each other for providing a composite strip having light longitudinal edge portions and a dark intermediate portion for resembling a complete skin of a lighter shade than the said rabbit skin.

2. A method of making fur skins for use in the manufacture of fur coats comprising 90 cutting of a longitudinal strip of skin from one side of a rabbit skin, said strip comprising substantially equal longitudinal sections of the belly portion of that side of said rabbit skin and the adjacent back portion of said 95 rabbit skin, the cutting of a longitudinal strip from the other side of said rabbit skin comprising substantially equal sections of the belly portion of the other side of said skin and the adjacent back portion thereof, 100

and sewing of said strips together for resembling a complete skin of a lighter shade than the said rabbit skin.

3. A method of making fur skins for use in the manufacture of fur coats comprising cutting of a longitudinal strip of skin from one side of a rabbit skin, said strip comprising substantially equal longitudinal sections of the belly portion of that side of said rabbit skin and the adjacent back portion of said rabbit skin, the cutting of a longitudinal strip from the other side of said rabbit skin comprising substantially equal sections of the belly portion of the other side of said skin and the adjacent back portion thereof, and sewing of said strips together, with the edges of the back section thereof attached to each other for resembling a complete skin of a lighter shade than the said rabbit skin.

20 4. A method of making fur skins for use in the manufacture of fur coats comprising the longitudinal cutting of strips of skin from the side portions of said rabbit skin each comprising a longitudinal section of light colored fur and a longitudinal section of dark colored fur, sewing of said strips together with the section of dark colored fur adjacent each other for providing a composite strip of fur having a dark intermediate portion and light side portions and sewing of like composite strips together for forming goods for a coat.

5. A method of making fur skins for use in the manufacture of fur coats comprising cutting of the side portions of a rabbit skin intermediate the longitudinal extremities of the belly portion of one side thereof, cutting

of the same side of said skin intermediate the back portion thereof for forming a strip comprising a longitudinal section of light fur from the belly portion of said skin and an adjacent integral section of dark fur from the back portion thereof, cutting of the other side of said rabbit skins intermediate the longitudinal extremities of the belly portion thereof, cutting of the second mentioned side of said skin intermediate the back portion thereof for forming a strip comprising a longitudinal section of light fur from the belly portion of said skin and an adjacent integral longitudinal section of dark fur from the back portion thereof, and stitching of said strips together with the dark section attached to each other for forming a composite strip having a dark middle portion and light side portion for resembling a complete skin of a lighter shade than the said rabbit skin.

6. Goods for the manufacture of fur coats comprising a plurality of composite strips of fur stitched together, each composite strip comprising two strips of rabbit skin each having a longitudinal section of dark colored fur and an adjacent integral longitudinal section of light colored fur stitched together, with the section of dark colored fur attached together for forming fur goods of a relative lighter colour than when made from complete rabbit skins.

In testimony whereof we have affixed our signatures.

BENJAMIN GREENBERG.
